UNITED STATES PATENT OFFICE

AUGUSTUS W. NEWELL, OF DETROIT, MICHIGAN.

IMPROVEMENT IN BOTTLES AND STOPPERS.

Specification forming part of Letters Patent No. **152,158**, dated June 16, 1874; application filed January 7, 1874.

To all whom it may concern:

Be it known that I, AUGUSTUS W. NEWELL, of Detroit, in the county of Wayne and State of Michigan, have invented certain new and useful Improvements in Bottle Necks and Stoppers; and do hereby declare that the following is a full, clear, and exact description thereof, reference being had to the accompanying drawings making a part of this specification, in which—

Figure 1 is a perspective view of the upper portion of a bottle containing my improved stopper. Fig. 2 is a vertical central section of the same upon a line passing through the discharge-passage and air-vent, said stopper being turned so as to close said openings; and Fig. 3 is a like view of said bottle, its stopper being arranged so as to inclose its vent and discharge-passage.

Letters of like name and kind refer to like parts in each of the figures.

The design of my invention is to enable the liquid contents of a bottle to be discharged without removal of its stopper, and also to enable the quantity of such liquid that is permitted to escape to be easily controlled; to which end it consists in the combination of a bottle provided at opposite sides of its neck with radial openings, with a stopper which closely fills said neck, and is provided with passages which may be caused to coincide with and extend between said openings and the interior of said bottle, substantially as and for the purpose hereinafter specified.

In the annexed drawing, A represents the neck of a bottle having the usual cylindrical interior, and provided, at a short distance below its upper end, with two lateral openings, *a* and *a'*, which extend radially outward from opposite sides. The outer ends of these openings may, if desired, come flush with the sides of said neck, but for convenience I prefer to extend them outward in the form of a pipe, as shown. Within the interior of the neck A is placed a stopper, B, which stopper has the same shape and dimensions as said interior, and when in position with its upper enlarged end *b* just above the end of said neck, so closely fills the space as to prevent leakage or accidental displacement. Within opposite

sides of the stopper B are formed passages *b'* and *b''*, which may be caused to coincide with the openings *a* and *a'*, and from the latter communicate with the interior of said bottle, so as to permit the liquid contents of the same to escape outward and air to enter.

The operation of the device is as follows: When the bottle is not in use its stopper is turned to the position shown in Fig. 2, and effectually cuts off communication between the exterior and interior of said bottle. When it is desired to discharge a portion of the contents of the bottle the stopper is turned until its passage coincides with the lateral openings in the neck, and said bottle then tilted until the liquid will flow through one of the passages *b'* and from its corresponding opening *a*, air to supply the place of such liquid being admitted through the opposite upper passages. By placing the thumb over the upper opening or air-vent, and admitting air slowly through the same, the speed with which the liquid is discharged, and the quantity discharged, may be regulated with the utmost nicety.

The especial advantage obtained by this construction is the ease and certainty with which the contents of the bottle may be discharged; but a farther and important advantage consists in the protection afforded against the loss of the stopper, there being no occasion for the removal of the latter, except when it becomes necessary to fill or clean said bottle.

Having thus fully set forth the nature and merits of my invention, what I claim as new is—

The bottle-neck A, provided at opposite sides with radial openings *a* and *a'*, in combination with the stopper B, having passages *b'* and *b''*, which may be caused to coincide with said openings and afford communication between the same and the interior of the bottle, substantially as and for the purpose specified.

In testimony that I claim the foregoing I have hereunto set my hand this 12th day of December, 1873.

AUGUSTUS W. NEWELL.
